COAT HANGER COVER APPLYING MACHINE

Abner L. Madsen, Mundelein, Ill.

Application August 24, 1956, Serial No. 606,139

7 Claims. (Cl. 53—200)

This invention relates to automatic cover applicators for ordinary wire clothes hangers to render them useful in the safe handling of clean clothes.

In many of the better cleaning establishments where the ordinary wire coat hangers are commonly used in the handling of the cleaned garments, a paper cover has been used over the hanger to protect the clothes from any dirt or rust on the hanger as well as to keep them from possible snagging on any rough spots that are occasionally found on parts of the wire that may come into contact with some delicate clothing materials. It has been customary to apply these paper covers, such as e. g. those shown in my prior Patent No. 2,566,232, to these hangers by hand. This becomes a tedious and time consuming process when a multitude of hangers are involved.

The present invention was devised to reduce the time and labor required for applying the covers to the hangers, as well as to minimize the cost.

The object of this invention is to provide a machine for automatically applying the above type of covers to the common type of wire clothes hangers on a mass production basis, starting with a continuous line of the clothes hangers and a stack of the die cut covers and ending with a line of covered hangers.

Another object is to devise a novel means for feeding the bare wire hangers one at a time in the above machine, with a sensing device for controlling the paper cover feeding means whereby to feed a cover only during the cycles of operation when a wire hanger has been started on its cycle through the machine.

A further object is to provide electro-magnetic anti-jiggling means to aid in stabilizing the movement of each individual hanger against rebound from guide plates against which it is fed at the beginning of each cycle of operation.

A further object is to provide means for centering the hanger over the horizontally fed cover sheet, as the hanger is dropped thereover, with its horizontal wire portion resting in a pair of release fingers just back of the corresponding edge of the cover and in line with a pair of resiliently pressed feed rollers positioned below the cover sheet, and means for then opening the release fingers and pushing the hanger down to fold the cover upwardly over said horizontal wire portion and start the hanger with the cover downwardly through these feed rollers into a lower station.

A further object is to provide means for feeding one cover sheet at a time from a stack horizontally into position against a back stop over said pair of pressure rollers in response to said sensing device whenever a hanger has been started on its cycle.

A further object is to provide a horizontally reciprocating support for receiving the hanger in said lower station and, after it has been turned into its horizontal position and the upper corners of the cover simultaneously drawn over the slanting sides of the hanger, feeding its hook end between two laterally spaced side pairs of

2

horizontal pressure rollers to guide the sides of the hanger into and through these rollers whereby to fold, press and seal the cover corners over the inside surface of the intermediate portion of the cover.

5 A further object is to provide a flipper means for flipping the hanger over from its vertical position resting on said support to its horizontal position thereon prior to reciprocation of the support to feed the hanger into the two pairs of rollers, to provide centering means for centering the hanger against said flipper before the flipping operation, and to provide an opening in a wall through which the hanger is flipped, having slanting edges coextensive with the slanting hanger sides, whereby the upper corners of the cover are simultaneously drawn over the hanger sides and folded thereover by the pairs of pressure rollers as the hanger is fed horizontally therebetween by the reciprocating support.

10 A further object is to provide a collector rod with an elevated hook end for receiving the covered hangers as they emerge from said pairs of rollers.

15 A further object is to provide safety cut-off means for stopping the machine in the event of jamming of the flipper means due to accidental misalignment of the hanger with the opening through which it is flipped.

20 Other and more specific objects of this invention will become apparent in the following detailed description of a preferred form of construction of the machine as illustrated in the accompanying drawings, wherein:

25 Fig. 1 is a perspective view of the complete machine,
30 Fig. 2 is a right side elevational view with part of the near side cover plates removed,

35 Fig. 3 is a left side elevational view of the rear portion of the machine with the near side of the frame work removed to show the internal arrangement of parts,

40 Fig. 4 is a front elevational view of the machine,
45 Fig. 5 shows the flipper operating cam groove and lever mechanism on the left side of the machine.

Fig. 6 is an enlarged detail plan view of the driving gears for the hanger supply and guide rods,

50 Fig. 7 is an enlarged detail plan view of the lower centering means for the hanger at the flipper station.

Fig. 8 is an enlarged detail elevational view of the solenoid operated vacuum-breaking valve,

55 Fig. 9 is a schematic perspective view of the operating parts showing the path that the hanger and cover take in going through the machine,

Fig. 10 is a plan view of a cover sheet showing bands of pressure adhesive applied thereto to provide adhesion of the folded edge and upper corners when folded over the hanger wire and pressed between the respective pressure rollers, and

60 Fig. 11 is an elevational view of the hanger with the cover applied.

65 The machine illustrated in the drawings comprises a generally rectangular framework substantially closed on the sides and the lower portion of the front.

The bare wire hangers 20 are hung over the upper of a pair of vertically spaced parallel shafts 21 and 22 extending from bearing supports 23 and 24 at the top rear of the machine to a slightly lower height near the front, to provide a slight incline for urging the hangers hanging on the smooth portion of shaft 21 at the rear toward the helically grooved front portion 25, as the shafts 21 and 22 are continuously turned during operation of the machine, so that the hanger hooks may be picked up one at each turn of the shaft by the tapered upper end of the thread forming the groove, and fed in the successive turns of the groove toward the lower open end of shaft 21, which has a tapered hook 26 for catching the hanger as it emerges from the last turn of the groove and releasing it after turning a further 90° or more. Shafts 21 and 22 are geared together for rotation in op-

posite directions by gears 27 and 28, and are driven through bevel gears 29 and 30 by the chain sprocket 31 on shaft 32.

Chain sprocket 31 is driven by chain 33 from sprocket 34 on the drive shaft 35, which is driven by sprocket 37 and chain 38 from the sprocket 39 on shaft 40, which has another sprocket 41 and chain 42 for driving the other operating parts of the machine in timed relation through successive cycles of operation, as will be more fully described hereinafter.

The vacuum and pressure air supply pump 36 for maintaining a source of vacuum 43 and a source of pressure 44, is driven independently by motor 45 through belt 46 and suitable pulleys 47 and 48. The sources 43 and 44 are connected by suitable tubing 49 and 50 with the paper cover sheet feeding means in a well known manner to assist in picking up the cover sheets one at a time at the proper times in the cycles of operation and dropping them at the entrance to the feed conveyor 51, for conveying each sheet horizontally forward, over the roller shield 52 and up against the backstop 53 in time for the hanger to be dropped and fed downwardly to fold the edge of the cover over the horizontal portion of the wire hanger as it passes down through the rollers 54 and 55.

The suction tubing 49 is connected through a manifold 56 for distributing the vacuum, to the suction cups of the feeding mechanism for lifting the top cover sheet from the stack. A pivoted flap 57 is normally held resiliently in closed position over an aperture in the manifold 56. A solenoid 58 opens this aperture by moving the flap off of it, to break the suction and prevent feeding a cover sheet during a cycle when no coat hanger is fed by the groove 25 of rod 21. The solenoid circuit is closed only at the instant in any cycle when the cover feed suction cups would normally be picking up a cover sheet, but no hanger has been released to operate the normally closed micro switch 59 to break the circuit. Switch 59 is in series with micro-switch 60 which is normally open and is closed cyclically by cam 61 only during the pick up period of the cover sheet feeding means. Switches 59 and 60, being in series, will close the solenoid circuit to operate and thus prevent feeding a cover sheet only when a hanger is not started on its cycle through the machine, thus assuring that every sheet fed will be removed by a hanger on its cycle through the covering process, before a new sheet is fed against the back stop 53 after the next hanger is started on its cycle.

It will be understood that the drive means for the cover sheet feeding mechanism is through positive chain sprocket and gear means from the common or main drive shaft 40 which also drives the hanger feeding and processing means in timed cyclical sequence. However this shaft 40 is driven by motor 63 through a belt 62, a suitable gear reduction 64 and friction clutch means 65 which will give at a predetermined overload torque to prevent damage to the operating means in case of jamming at any particular point in the machine. The motor 63 may be provided with an automatically adjustable drive pulley 66 for adjusting the speed of operation of the machine by moving the motor on its base to change the distance between pulleys 66 and 67 and thus changing the effective diameter of the pulley 66. This pulley is of well known construction, having its V-groove formed by opposed discs axially biased toward each other to urge the V-belt 62 radially outwardly to take out its slack when the motor is moved to bring the pulleys closer to each other, and to permit the V-belt to ride deeper in the groove by separating the discs further apart and thus provide a smaller effective pulley diameter when the motor is adjusted on its base to move the pulleys further apart.

Referring now more particularly to Fig. 9, as the machine is operated, a hanger 20 normally emerges at

the lower end of the groove 25 onto the tapered hooked end 26. In sliding down the tapered end after leaving the groove, the hanger dangles haphazardly until its hook reaches the hooked end of the taper and its lower horizontal wire portion approaches the front guide plate 68. At this time in the cycle of operations a normally open micro-switch 69 is operated by a cam on the shaft 70 to complete a circuit through the stabilizing solenoid 71 which is mounted in an opening in the guide plate 68, flush with the rear surface thereof. The solenoid is thus energized and draws the hanger up against the rear surface of the plate and stops it from bouncing around, so that when the hook on the tapered end of rod 21 has turned to release the hanger and the solenoid has been deenergized, the hanger will fall straight down back of the guide plate 68, between the idle roller 72 and its companion part roller 73, into the closed fingers 74 at a level just above the pair of rollers 54 and 55. At this instant the centering jaws 75 and 76 are swinging inwardly against the corners of the wire loop of the hanger, while in the meantime a cover sheet 77 has been fed through the belt conveyor 51 into position with its forward edge over the pair of rollers 54 and 55, up against the back stop 53.

The next step in the cycle of operations is the opening of the fingers 74 to release the hanger, followed immediately by the partial roller 73 rolling against the idle roller to resiliently grasp the upper part of the hanger therebetween and force it downwardly, causing its lower horizontal portion to pick up the cover sheet, creasing its edge and folding it over this horizontal wire portion as the rollers 54 and 55 resiliently receive the combined hanger and cover, sealing the edge of the cover over at the adhesive strip portions by pressing them together. As the hanger with the cover emerges from these rollers 54 and 55, it drops to the reciprocating support 78, and is held in an upright position between the back of the flipper 79 and the front of guide plate 80, as shown in the schematic diagram of Fig. 9.

At this time another bare hanger may be started on its cycle as shown in this figure, and a cover sheet 77 fed through the belt conveyor 51. In this manner the covering process may be carried out in quick succession on the hangers automatically and continuously, as long as a supply of bare hangers is maintained at the top of the rod 21 and the finished, covered hangers are periodically withdrawn from the lower rod 81.

Immediately after the hanger with the cover is dropped to the support 78, a centering pair of jaws 82, positioned near the top of the flipper, are operated to move the hanger laterally into position, with its hook shank aligned with the narrow neck portion of the flipper 79.

The flipper is then operated to turn the hanger down flat on the support 78, by pushing it through the opening in the guide plate 80 with flexible triangular side flaps extending from the angular sides of the opening so as to flex the upper corners of the cover sheet over the angular wire portions of the hanger. Thus, when the support 78 is then moved back in its horizontal reciprocation, its lugs 83 will push the hanger backward and the hanger sides in between the side pairs of rollers 84 which will receive them resiliently and press these upper corners of the cover sheet over the inner surface of the cover sheet as the rollers continue to pass the hanger therethrough, to firmly stick the contacting strips of adhesive on the cover sheet together to hold the cover sheet folded in place. As the hanger emerges from these side pairs of rollers, its hook end moves horizontally over the raised open end of the receiving rod 81, so that it is caught in a hanging position thereby and slides downwardly thereon toward the other hangers previously caught by the rod and gathered at the rear lower end of the rod. The finished covered hangers have to be removed at intervals to provide room for the successive accumulation of covered hangers during continuous operation of the machine.

The cover sheets 77 may be supplied in stacks, their adhesive surfaces uppermost, on the vertically adjustable table 84 and the table adjusted manually to bring the top of the stack to the proper feeding level. The table 84 may be slidably mounted between vertical guide posts 85 and hung by a chain 96 passed over a sprocket 86 at the top of one of the posts, which is provided with a worm gear 87 and worm 88 for irreversible adjustment either by a manually operated hand wheel 89 or automatically through clutch 90 by bevel gears 91 from the machine power drive system to raise the table in response to a control switch 92 for operating the clutch 90 which is normally disconnected, into connected position. The control switch 92 which is snapped closed by a cam 93 on shaft 94 operated by level sensing lever 95 the outer end of which rests on the top of the stack of cover sheets. When the stack is raised sufficiently the cam snaps the switch open to disconnect the clutch until the top of the stack becomes too low again for proper feeding. Thus the level of the top of the stack is automatically kept within operative limits as the stack is reduced, until used up. The table 84 may be counterbalanced by weights on the free end of the chain 96 to reduce the load on the adjusting mechanism, if desired.

The belt conveyor 51 may be driven by belt 97 from a large pulley 98 on shaft 99. Belt 97 drives small pulleys on conveyor shafts 100 and 101 in one direction for the lower set of rollers and shaft 102 in the opposite direction for the upper set of rollers to cause their adjacent conveyor belts to move in the feeding direction.

Shaft 99 is one of the cyclically operated shafts of the machine for driving the partial roller 73 and the micro-switch cams 61 and 70, as well as the cam 103 for opening the fingers 74, and the two cam grooves 104 and 105 for operating the swinging centering jaws 75 and 76 respectively in proper timed relation as described. This shaft also carries a cam 106 for operating the bell crank 107 to close the lower centering jaws 82 through lever 108 and links 109 operating in a horizontal plane.

Drive chain 42 passes from drive sprocket 41 over sprocket 110 as shown in Fig. 2, then sprocket 111 on shaft 112 for driving the pairs of side rollers 84, then upwardly over sprocket 113 for driving shaft 99, then downwardly over idling sprocket 114 on the shaft 115 of roller 54, and back to sprocket 41. Roller 54 is driven from the shaft 116 of roller 55 by matching gears 117 on the two roller shafts. Shaft 116 has a sprocket 118 driven by chain 119 from a sprocket 120 on shaft 99 so as to drive the rollers 54 and 55 in the proper feed direction.

A companion sprocket fixed alongside of sprocket 110 is connected by chain 121 to a sprocket 122 on shaft 123 for operating roller arm 124 to operate the bell crank 125, the other arm of which is connected to the reciprocating support 78 by link 126.

Support 78 is cut-away at its rear end to move in the space between the side pairs of rollers 84. It is normally resiliently held in its forward position as shown in Fig. 3 by the axially extending expansion spring 127 and two side compression springs 128 mounted around guide bolts 129 on which the support 78 is slidably mounted. When in retracted or forward position the rear end of the support will not interfere with the dropping of the lower horizontal edge of the hanger as it swings down over the lower of the side pairs of rollers and its hook catches over the end of rod 81.

Shaft 112 extends through the left side of the machine frame and is provided with an eccentric groove cam 130, in which a pin in yoke arm 131 is guided by the yoke of the arm being saddled over the end of the shaft 112, thus moving the arm substantially axially to oscillate the arm 132 on the shaft 133 for turning the flipper through substantially 90° at the proper time as described. A spring 144 may be connected to the arm 132, as shown, to take up the play in one direction.

The shaft 133 includes a cross pin 134, in one portion

of the shaft, resting in a V-groove of an axially biased collar 135 slidably keyed to an adjacent portion of the shaft for transmitting the torque between the portions during operation, so that if a hanger gets jammed between the flipper and other parts of the machine, the flipper or other parts will not break, because this safety joint will give. The pin will merely force the collar to slide axially on its keyway as it slips out of the V-groove. The axial movement of the collar will operate a safety cut-off micro-switch 136 which breaks the power circuit and stops operation of the machine, so that the trouble may be taken care of before operation is resumed.

Bridge plates 137 and 138 at opposite ends of the belt conveyor 51 are for guiding the cover sheets over the spaces between the conveyor and the stack of cover sheets at one end and the feed roller 55 at the other end.

A switch box 139 with starting and stopping push buttons 140 and 141 may be mounted at the top of the machine, as shown.

20 The suction and pressure cups 142 are operated in a well known manner to pick up the top cover sheet and move it into the conveyor 51 as already described, in cyclic cooperation with the feed of the hangers.

The cover sheets 77, as disclosed in my prior patent, are 25 provided with a coating of pressure type adhesive 143 applied in four strips on one side of a sheet as shown more specifically in Fig. 10. This type of adhesive will not stick even with the application of considerable pressure to any uncoated surfaces, but when pressed against similarly coated surfaces it will readily stick firmly thereto.

30 Thus when the lower edge is folded over the horizontal wire portion of the hanger and pressed between the feed rollers the adhesive strips are pressed over each other and seal themselves together. Similarly when the upper 35 corners are folded and pressed between the rollers, considerable portions of the adhesive strips are sealed together to hold the cover sheet firmly in place over the hanger frame as shown in Fig. 11.

Many obvious modifications in the form and arrangement of parts may be made without departing from the spirit and scope of this invention, as defined in the appended claims.

What is claimed is:

1. A cover applying machine for wire coat hangers, 45 comprising a hanger pole for receiving a supply of coat hangers of conventional wire construction, a table for receiving a stack of cover sheets having suitable adhesive coatings on their upper surfaces, and cyclically operated means including means for bringing together a cover sheet from the top of said stack and a hanger from the end of the said pole, means for properly aligning said hanger with respect to said sheet, means for folding an edge of the sheet over the horizontal wire portion of said hanger and pressing its adhesive portions to seal them together, means for folding the upper corners of said sheet over the angular side wire portions of said hanger and similarly sealing them to the inside surface of said sheet, and a raised open ended pole for receiving said covered hangers and accumulating them by sliding thereon toward its supported lower end, and sensing means for interrupting the bringing of a sheet in any cycle when a hanger is not delivered from the end of the pole.

2. A cover applying machine for wire coat hangers, 55 comprising a hanger pole for receiving a supply of coat hangers of conventional wire construction, a table for receiving a stack of cover sheets having suitable adhesive coatings on their upper surfaces, and cyclically operated means including means for bringing together a cover sheet from the top of said stack and a hanger from the end of the said pole, means for properly aligning said hanger with respect to said sheet, means for folding an edge of the sheet over the horizontal wire portion of said hanger and pressing its adhesive portions to seal them together, means for folding the upper corners of said sheet

60 over the angular side wire portions of said hanger and

70

75

similarly sealing them to the inside surface of said sheet, and a raised open ended pole for receiving said covered hangers and accumulating them by sliding thereon toward its supported lower end, said means for bringing the sheet and hanger together comprising means for feeding said sheet forwardly to a position against a stop, and means for releasing a hanger from the end of said hanger pole and dropping it to a position directly over said sheet just back of its forward edge.

3. A machine as defined in claim 2, a pair of fingers normally biased into closed position slightly spaced over said sheet to catch and hold said hanger in its position directly over said sheet, said aligning means including centering jaws at the outer corners of the hanger frame for centering it with respect to said sheet in case it fell off center in falling into the fingers, and means for then opening said fingers and pushing said hanger down on said sheet.

4. A machine as defined in claim 3, said edge folding means including a pair of rotating hard rubber pressure rollers directly under said sheet for receiving the horizontal wire portion of the frame with said edge of the sheet folded over it to press and seal said edge to the inside surface of said sheet as the hanger and sheet are fed through said rollers.

5. A machine as defined in claim 4, a flipper, a vertical guide plate behind it, and a horizontally reciprocable support below them for receiving said hanger and partially attached sheet on the front of said support between the flipper and guide plate, means for then centering said

10

15

20

25

30

hanger and sheet with respect to said flipper, said guide plate having an opening corresponding substantially to the outline of said hanger and having resiliently flexible flaps extending from the angular sides of the opening, said upper corner folding means including means for operating the flipper to turn the hanger down on said support, the flaps drawing the upper corners of said sheet over the angular side wire portions of said hanger, a pair of resiliently pressed rotating rollers on each side of the hook portion of said hanger, means for then reciprocating said support to start said hanger through said pairs of rollers, said support having lugs back of the straight edge of said hanger to push it for starting through said rollers, and an inclined pole having its upper open end in position to receive the hook portion of the hanger as it emerges from said side pairs of rollers for slidably accumulating said hangers toward its lower end.

6. A machine as defined in claim 5, said flipper having a shaft with maximum torque safety release joint to prevent breakage of parts in case a hanger jams the flipper.

7. A machine as defined in claim 6, and a safety microswitch operative in response to such release of said joint to cut off the machine operation, whereby the trouble can be remedied before resuming operation.
